UNITED STATES PATENT OFFICE.

PASQUALE PASCALE, OF NEW YORK, N. Y., ASSIGNOR TO DRI-STEAM VALVE CORPORATION, OF NEW YORK, N. Y., A CORPORATION OF DELAWARE.

SEPARATOR.

Application filed March 31, 1927. Serial No. 180,048.

This invention relates to an apparatus for separating the gasiform content and the liquid content of a saturated fluid, as water or moisture from air, and controlling the flow of the same.

An object of the invention is to provide a structure of this character, in which the moisture or condensate, when separated from the air or fluid, will fall to a point below 10 and be trapped below the current of incoming air, thus preventing it from being carried on with the currents, and to provide a structure wherein the surfaces of impingement of the saturated fluid will be 15 greatly increased in a given area, so as to break the fluid up into small parts to insure the complete separation of the liquid from the air, and also a structure in which the conduit for getting rid of the moisture or 20 water is conveniently within the body of the casing.

Another object of the invention is to provide a separator which will be exceedingly simple in construction, and one in which 25 the air for instance, may be thoroughly dried before passing to the point where the dry air is desired, associated with means for controlling the flow of both the air and the condensates.

30 In the drawing illustrating the invention:

The figure is a section of the valve, with portions thereof in elevation.

Referring to the drawing the numeral 1 35 designates the valve body flanged at its lower end as indicated at 2, for attachment to a reservoir or tank from which air reaches the valve, under pressure. To one side of the valve casing, is another flange 3, for the connection of the outlet or service pipe. The inlet is indicated by 4 and the outlet by the numeral 5.

The upper part of the valve body is constituted by a head 6 held to the lower part 45 of the body by bolts 7. The head is provided with a yoke 8, serving as a part of the means for supporting the hand wheel and valve stem as will be more particularly described.

50 The numeral 9 indicates the air drier. This, when its parts that compose it, are assembled, forms two concentric walls an outer wall 10, and an inner wall 11, so arranged that when the wall portions are

assembled an annular chamber 12 will be 55 formed. This chamber is entirely closed at its top, and closed at its bottom with the exception of a comparatively large drain hole or opening 13, and a series of small apertures or openings 14, communicating 60 with the chamber 12. The inner wall 11 is provided throughout the upper part of its circumference, with numerous small holes or openings 15, constituting nozzles. These are preferably flared, slightly from the inside of the walls toward the outside thereof. Integral with, and also forming a part of the inner wall of the chamber 11 is a peculiarly formed annulus 16, having a lip 17, spaced away from the inner wall of the 70 inner chamber thus providing a pocket 17' between the lip and wall for a purpose that will presently appear. The upper end of this wall is provided with a flange 19, which overlaps the flange 20, on the outer wall 75 of the drier. These two parts are firmly secured together by short bolts 21. The lip 17 of the annulus 16, is spaced from the inner wall of the drier to form an annular pocket 17' as stated, which communicates 80 through one or more small openings 23, with the chamber 12, between the inner and outer walls of the drier, as clearly shown. Communicating with the opening 13 in the bottom of the chamber 12, between the drier 85 walls is a conduit 24 formed in the neck of the body or casing. The lower end of this conduit is threaded, as indicated at 25, for the reception of a bleeder pipe 26, which pipe may lead back into the reservoir or 90 tank, or may be so arranged as to lead to the outside thereof, to provide means for getting rid of the fluent condensate that has been removed from the air.

95 Surrounding the drier and spaced therefrom, is a seat ring 27 which is threaded into the valve casing as shown. This seat is provided at its upper inner edge, with a bevelled portion 28, shaped for contact with a similarly bevelled portion 29 on the valve disk 100 30. This valve disk is provided with a plurality of legs 31 which overlap and engage the outer periphery of the drier, thus serving as a part of the guiding means for the valve in its opening and closing movements. 105 The upper part of the valve disk is recessed, as indicated at 31, and internally threaded as indicated at 32 for the reception of a nut

33. This nut has an opening 34 for the passage of the reduced portion 35 of the valve stem head 36. The valve stem 37 is integral with the head and is guided in a 5 nut 38 threaded into the underside of the head 6 of the casing. The valve stem is prevented from turning and the nut 33 is held in position by a cotter pin 39, passing through said nut, and the boss 40 formed on 10 the valve disk. The valve stem extends through the nut 38, and through a guide 41, and is provided with a thread 42, formed on the upper part thereof, the threaded portion passing through a similarly threaded hub 15 43, of the hand wheel 44, the rotation of which wheel serving to raise and lower the valve disk to seat or unseat the valve. A space is left between the sleeve 41 and nut 38, in which suitable packing may be placed. 20 The upper part of the surface of the inner and outer walls on the inner side of each, is corrugated or undulated as indicated respectively by the numerals 45 and 46, thereby within a given area providing greatly increased surfaces against which the air forcefully impinges, causing it to be broken up 25 into small parts, and thus causing the moisture to be more readily separated from the air. 30 The drier is provided at intervals with bosses 47. These have sockets in them for the reception of the ends of bolts 48, whereby the drier is held firmly in position within the casing. 35 As shown in the drawing, I may provide a bore in one or more of the bolts 48 as indicated at 49, and provide a small hole 50 in the outer wall of the drier, near its bottom, to permit the water to leave the bottom of 40 the chamber 12 through an outlet pipe 51, which pipe would be capped when it is not desired to use this form of outlet. However, when it is desired to use it, the conduit 24 45 may be plugged at its lower end instead of having therein as shown, a bleeder pipe. 50 The saturated fluid passes into the valve through the inlet 4 under pressure. When the valve is open the fluid will impinge first forcefully against the corrugated surface of the inner wall of the drier, and the moisture therefrom will fall into the pocket 17, from which it will flow into the chamber 12 55 through the small openings 23. The less saturated fluid will again pass through the nozzles or openings in the outer wall of the drier, and any moisture that has been left in it, after passing through the openings in the inner wall will be removed or extracted, and will fall to the bottom of the chamber 12 60 and out of the chamber 12 the liquid condensate will pass through the conduit 24 and the air thoroughly dried after passing through the outer wall of the drier will pass to the point where it is desired or required. 65

It will be understood that in opening and closing the valve the movement of the valve disk is never so much as to break the contact of the inner bearing surface of said disk with the outer periphery of the drier, hence all 70 fluid that passes through the valve must pass through the holes or perforations in the walls of the drier.

It will be noted that the pocket 22, and the lower part of the chamber 12 are both 75 below the openings or nozzles in the walls of the drier. This, as before intimated is for the purpose of removing the extracted moisture or water from the path of the currents in passing through the valve.

The term fluid throughout is used in its broadest sense, and the term corrugated in the specification and claims is intended to mean any formation of the impinging surfaces of the drier whereby the impinging 85 surface, within a given area, is increased.

As just stated, the term "fluid" throughout the specification is used in its broadest sense, which of course includes "steam" from which obviously the separator is well 90 adapted to "dry" or extract the moisture.

Claims:

1. In a valve of the character described, in combination, a hollow body having an inlet and an outlet opening, a valve seat between the two openings, a stop valve adapted to seat on said seat, a drier in said body between the openings comprising in the main, two corrugated walls upon which the saturated fluid, passing through the valve, impinges, said walls being spaced apart to form a chamber therebetween closed at one end and open at the other, the walls being provided with numerous small holes constituting nozzles, said drier having one open end and having its other end adapted to be closed by said valve whereby fluid is caused to flow through said nozzles, the corrugated surfaces of the drier serving to increase the area of the surface of impingement of said fluid, for the purpose set forth.

2. In a valve of the character described, in combination, a hollow body having an inlet and an outlet opening, a valve seat between the two openings, a stop valve adapted to seat on said seat, a drier in said body between the openings comprising in the main, two corrugated walls upon which the saturated fluid, passing through the valve, impinges, said walls being spaced apart to form a chamber therebetween closed at one end and open at the other, the walls being provided with numerous small holes constituting nozzles, said drier having one open end and having its other end adapted to be closed by said valve, whereby fluid is caused to flow through said nozzles, the surface of the drier upon which the saturated fluid 125

impinges in passing through the body being corrugated, thereby increasing the area of the surface of impingement of said fluid, means on the inner wall to trap the condensate carried by the fluid means permitting the trapped condensate to flow to the chamber between the walls, means between the walls to trap the condensate formed therebetween, and means for draining said condensate from said chamber.

3. In a valve of the character described, in combination, a hollow body having inlet and outlet openings, a valve seat between said openings, and a valve adapted to seat on said seat, a drier in said body between the openings and in the path of the flow of the fluid through said body comprising a hollow member open at one end and having numerous small holes therein constituting nozzles, the other end of said member being adapted to be closed by said valve whereby the fluid is caused to flow through the nozzles, the surface of the body being corrugated thereby increasing the area of surface of impingement of said fluid, for the purpose set forth.

4. In a valve of the character described, in combination, a hollow body having inlet and outlet openings, a valve seat between the openings and a valve adapted to seat on said seat, a drier in said body between the openings, and in the path of movement of the flow of fluid through said body, and comprising two hollow members spaced apart to form a chamber therebetween, said members being provided with numerous small holes therein, constituting nozzles, one end of said members being open and the other end being adapted to be closed by said valve, whereby the fluid is caused to flow through the nozzles, the walls of the drier being so formed as to increase the fluid impingement surface within a given area.

5. In a valve of the character described, in combination, a hollow body having inlet and outlet openings, a valve seat between said openings and a valve adapted to seat on said seat, a drier in said body between the openings and in the path of the flow of the fluid through said body, comprising two hollow members spaced apart and provided with numerous small holes constituting nozzles, one end of said drier being open and the other end being adapted to be closed by said valve, whereby the fluid is caused to flow through the nozzles, the walls of the drier being opposite each other for substantially the entire depth of said walls.

6. In a valve of the character described, in combination, a hollow body having inlet and outlet openings, a valve seat between said openings and a valve adapted to seat

on said seat, a drier in said body between the openings and in the path of the flow of the fluid through said body, comprising two hollow members spaced apart and provided with numerous small holes constituting nozzles, one end of said drier being open and the other end being adapted to be closed by said valve, whereby the fluid is caused to flow through the nozzles, the walls of the drier being opposite each other for substantially the entire depth of said walls, and means for trapping the condensate carried by said fluid and forming on the inner surface of the drier, means for draining off said condensate, and means for trapping the condensate forming between the drier members, and means for drawing said last mentioned condensate.

7. In a valve of the character described, in combination, a hollow body having an inlet and an outlet opening, a valve seat in the body between the openings and a stop valve adapted to seat on said seat, a drier within the body between the openings, including a hollow sleeve provided with numerous small holes therein constituting nozzles, through which the fluid passes in passing through the body, the said valve being operable to control the passage of fluid through said nozzles, a lip on the fluid impingement wall of the sleeve, which, together with said wall, forms an annular channel for trapping the condensate carried by the fluid, the top of said lip being so positioned relative to the nozzles that the condensate trapped between the wall and the lip is trapped below said nozzles and out of the path of the fluid passing through said nozzles.

8. In a valve of the character described, in combination, a hollow body having an inlet and an outlet opening, a drier between said openings in the path of movement of the fluid passing through said body, and including a sleeve having numerous small holes therein constituting nozzles, through which the fluid passes, means for controlling the passage of the fluid through said nozzles, a lip on the fluid impingement wall of the sleeve, which, with said wall forms a channel for trapping the condensate carried by the fluid, the top of said lip being so positioned relative to the nozzles that the condensate forming between said wall and lip is trapped below said nozzles and out of the path of movement of the fluid passing through said nozzles.

In testimony whereof he affixes his signature.

PASQUALE PASCALE.
